UNITED STATES PATENT OFFICE.

FRANK F. KOLARIK, OF NUNN, COLORADO.

MECHANICAL TOY.

1,305,224.

Specification of Letters Patent. Patented May 27, 1919.

Application filed September 5, 1918. Serial No. 252,734.

To all whom it may concern:

Be it known that I, FRANK F. KOLARIK, a citizen of the United States, residing at Nunn, in the county of Weld and State of Colorado, have invented certain new and useful Improvements in Mechanical Toys; and I do declare the following to be a full, clear, and exact description of the invention, such as will enable others skilled in the art to which it appertains to make and use the same.

My invention has for its object to provide a simple and inexpensive, yet a highly amusing toy in which the figure of a boy attempting to steal an apple beneath an apple tree is unceremoniously struck by another figure normally hidden from view behind the trunk of the tree.

With the foregoing object in view, the invention resides in the novel construction and organization of parts as hereinafter fully described and claimed, and illustrated in the accompanying drawings.

Figure 1 is a front elevation of the toy illustrating the boy in the act of stealing the apple.

Fig. 2 is a view similar to Fig. 1, but showing the manner in which the second figure appears and strikes the boy.

Fig. 3 is a vertical section on the plane indicated by the line 3—3 of Fig. 1.

Fig. 4 is a detail vertical section showing a side elevation of the normally concealed figure and its operating means.

Fig. 5 is a view similar to Fig. 4 but illustrating a different position of parts.

In the drawings above briefly described, the numeral 1 designates a back plate which may be decorated in any preferred manner, 2 has reference to a horizontal flange extending forwardly from the plate 1, and the numeral 3 refers to another flange bent upwardly from the flange 2, said flange 3 having two vertically projecting portions 4 and 5, the portion 5 simulating the trunk of an apple tree, while the portion 4 may be of any desired design since it serves merely as a partial support for the figure 6 which represents the boy. This figure is pivotally mounted at 7 and is normally overbalanced so that one or both of its arms 8 come in close proximity with the representation 9 of an apple lying on the ground under the tree. The pivotal movement of the figure 6, caused by the overbalancing thereof is limited by a pin 10. It may here be ex- plained that both the pivot 7 and the pin 10 preferably extend through both the back plate 1 and the upstanding portion 4 to distribute the strain upon the two, and it may further be set forth that the support referred to in the claims is formed, in the present embodiment of the invention, by the parts 1, 2, 3, 4 and 5, but in other types of the device, the shape and construction of the support might well vary.

Normally hidden from view, behind the trunk 5, which latter is referred to in the claims as a view barrier, is a figure 11 simulating a man, this figure being pivotally mounted between its ends at 12 and having an arm 13 pivotally mounted upon the figure at 14. The arm 13 is provided with a projecting upper end 15 which is preferably of the hook shape shown, and when the upper portion of the figure is tilted forwardly by the means to be described, a guide pin or the like 16 projecting from the trunk 5 or from any other suitable part, engages the aforesaid extension 15, thus swinging the arm 13 upwardly and forwardly upon its pivot 14. This causes the arm 13 to strike the figure 6 and turn it from the position in Fig. 1 to that seen in Fig. 2. A suitable spring 17 is connected to the figure 11 for tilting it in a manner to expose its head to view as seen in Fig. 2, and for at the same time, swinging the arm 13 in the manner set forth. By means of a rod 18, however, the arm 13 and figure 11 may be held against operation until required. The rod 18 slides vertically and is provided with a lateral projection 19 adapted, when pulled downwardly onto the arm 13, to swing this arm downwardly upon its pivot 14 and consequently return the figure 11 to vertical position, thus placing the spring 17 under tension. The parts then stand as seen in Fig. 1, but the moment the rod 18 is pulled farther downward, the projection 19 releases arm 13 and the spring comes into action to operate said arm and the figure 11 in the manner above set forth, so as to strike the figure 6 and turn it completely over upon its pivot 7. This operation positions the feet of the figure 6 beneath the arm 13, as seen in Fig. 2 and by now giving the rod 18 a quarter turn to the right, sliding it upwardly and again turning it to position the projection 19 above the arm 13, a slight downward pull on the rod will cause said arm 13 to strike the feet of figure 6 and re-

turn it to the position of Fig. 1. A further downward pull of the rod moves the figure 11 to its obscured position in readiness for another operation.

5 From the foregoing it will be seen that although my invention is of extremely simple and inexpensive nature, it will afford a great deal of amusement. Since probably the best results are obtained from the 10 details shown and described they are preferably followed, but within the scope of the invention as claimed, numerous minor changes may well be made.

I claim:—

15 1. In a toy, a support, a figure movably mounted thereon, a second figure mounted on said support and having a movable limb arranged to strike and move said first named figure, a barrier normally obscuring said 20 second figure from view, and means for operating said movable limb to bring it into view and strike said first named figure.

25 2. In a toy, a support, a figure mounted movably thereon, a view barrier mounted on said support, a second figure mounted movably behind and obscured from view by said barrier, said second figure having a movable limb, and means for moving said 30 second figure into view and operating said movable limb to strike and move said first named figure.

3. In a toy, a support, a figure mounted movably thereon in the act of stealing an object, a view barrier mounted on said sup-

port, a second figure mounted pivotally 35 behind and hidden from view by said barrier, said second figure having a movable limb, and means for moving said second figure into view and for operating said movable limb to strike said first named figure and move the same away from said object.

4. In a toy, a support, a figure pivotally mounted on said support, an arm pivoted to the upper portion of said figure, said arm 45 projecting above its pivot, a spring for swinging said figure upon its pivot, a fixed stud in the path of said projecting part of the arm for swinging said arm outwardly upon swinging movement of said figure, and 50 means for holding said figure and arm in position to retain said spring under tension and for releasing said figure and arm when required.

5. In a toy, a support, a figure pivotally mounted on said support, an arm pivoted to the upper portion of said figure, a spring for swinging said figure upon its pivot, means for swinging said arm outwardly upon swinging movement of said figure, a 60 sliding control rod, and a lateral projection on said rod engaging said arm for retaining said spring under tension and for releasing said figure and arm when required.

In testimony whereof I have hereunto set 65 my hand.

FRANK F. KOLARIK.
